UNITED STATES PATENT OFFICE.

ERNST F. KLEMME, OF MILWAUKEE, WISCONSIN.

DESIGN FOR A VENT CONNECTION.

56,439.

Specification for Design.

Patented Oct. 26, 1920.

Application filed February 19, 1919. Serial No. 278,072. Term of patent 14 years.

To all whom it may concern:

Be it known that I, ERNST F. KLEMME, a citizen of the United States, residing at Milwaukee, in the county of Milwaukee and State of Wisconsin, have invented a new and original and ornamental Design for a Vent Connection, of which the following is a specification, reference being had to the accompanying drawing, forming part hereof.

In the drawing:

Figure 1 is a side view of a vent connection showing my new design;

Fig. 2 is a plan view; and,

Fig. 3 is an end view thereof.

I claim:

The ornamental design for a vent connection as shown.

ERNST F. KLEMME.

Witnesses:

R. S. C. CALDWELL,

H. D. CHASE.
